UNITED STATES PATENT OFFICE.

CHARLES C. KINSMAN, OF CHICAGO, ILLINOIS, ASSIGNOR TO UNIVERSAL DRAFT GEAR ATTACHMENT CO., OF CHICAGO, ILLINOIS, A CORPORATION OF ILLINOIS.

DRAFT-GEAR YOKE.

1,164,725.

Specification of Letters Patent. Patented Dec. 21, 1915.

Application filed January 21, 1914. Serial No. 813,410.

To all whom it may concern:

Be it known that I, CHARLES C. KINSMAN, a citizen of the United States, and resident of Chicago, county of Cook, and State of Illinois, have invented certain new and useful Improvements in Draft-Gear Yokes, of which the following is a specification, and which are illustrated in the accompanying drawings, forming a part thereof.

10 The invention relates to railway draft gears and more particularly to the part of such gears known as the yoke. It has heretofore been proposed to construct these yokes of two separable members with one of the 15 members taking the form of a socket for receiving the draw bar and the other member made in the form of a strap for encircling the cushioning elements. Yokes constructed in this way have been termed composite 20 yokes to distinguish them from the integral form. The composite yoke is desirable for the reasons that the assembling of the parts is facilitated and the use of different material, as cast metal for the socket member 25 and wrought metal for the strap is permitted. As heretofore constructed, however, difficulty has been experienced in providing a means of connecting the socket member and strap which will give to the 30 parts of the yoke the required strength for withstanding the shocks to which they may be subjected in service. The present invention accordingly contemplates a form of composite yoke having the socket member 35 and strap connected in an improved manner.

The object of the invention is to provide a draft gear yoke which may be readily constructed and which will be durable and efficient in use.

In the accompanying drawings, Figure 1 is a plan view of the yoke; Fig. 2 is a side elevation of the same, and Fig. 3 is a detail perspective view illustrating the end portions of the strap.

In the yoke shown in the drawings, the socket and strap members are generally designated by the reference numerals 10 and 11, respectively. The socket member 10 preferably comprises the two side walls 12 and 13 and the top and bottom walls 14 and 15. The side walls 12 and 13 have the usual horizontally disposed registering key receiving slots 16. In order that these slots may be of the required length, the side walls 12 and

13 are desirably made longer than the top and bottom walls 14 and 15, as by being provided with forwardly extended portions, designated 17 and 18, respectively. To permit lateral swaying of the draw bar (not shown), the forwardly extended portions 17 and 18 of the side walls 12 and 13 preferably flare outwardly as appears in Fig. 1.

The body portion of the strap 11 preferably has the usual U-shaped form for encircling the cushioning elements of the draft gear. In carrying out the present invention the two end portions of the strap are preferably widened and thickened to provide a T-head, as 19, 20 and a rearwardly facing shoulder 21, 22 at each end of the strap. If now the parts of the yoke are assembled by drawing the strap 11 rearwardly through the socket 10, the laterally projecting arms of each of the T-heads 19, 20 of the strap will ride upon the adjacent edges, as 23, of the extended portion 17, 18, of the side walls 12 and 13 of the socket member 10 and the rearwardly facing shoulders 21 will engage the forward edge of the top or bottom wall 14, 15, as a stop. A firm bearing between the ends of the yoke and the socket is thereby provided for the transmission of pulling strains and at the same time a support is provided between the ends of the strap to resist such strains as tend to turn the ends of the strap inwardly. Furthermore, relative movement between the socket member 10 and strap 11, as when the gear is subjected to buffing strains, is accompanied by a sliding of the arms of the T-heads 19, 20 upon the edges, as 23 of the side walls 12 and 13. The strap 11 with its T-heads 19 and 20 and rearwardly facing shoulders 21 is of a form which may be conveniently manufactured from wrought metal and when assembled with the socket member 10 a yoke of unusual strength is provided.

I claim—

1. In a draft gear yoke, in combination, a draw bar socket having top, bottom and side walls and open ends, the side walls being extended forwardly beyond the top and bottom walls, and a strap, the ends of which extend through the socket and each of which is widened to form a T-head with the arms of the T-head riding upon the adjacent edges of the said extended portions of the side walls of the socket.

2. In a draft gear yoke, in combination, a

draw bar socket having top, bottom and side walls and open ends, the side walls being extended forwardly beyond the top and bottom walls, and a strap, the ends of which extend through the socket and each of which is widened and thickened to form a T-head and a rearwardly facing transverse shoulder with the arms of the T-head riding upon the adjacent edges of the said extended portions of the side walls of the socket and the said transverse shoulders abutting against the forward edges of the top and bottom walls of the socket.

3. In a draft gear yoke, in combination, a U-shaped loop having lateral projections at the ends of its side members, and a draw-bar engaging member having upwardly fac-

ing shoulders and forwardly facing shoulders for engaging such projections.

4. In a draft gear yoke, in combination, a draw-bar socket having top, bottom and side walls, the side walls extending forward of the top and bottom walls and being of less vertical width than the distance therebetween, a U-shaped strap having its ends extended through the socket and being provided with lateral projections bearing, respectively, against the top and bottom edges of its side walls and against the forward edges of its top and bottom walls.

CHARLES C. KINSMAN.
